US00D997982S

(12) **United States Design Patent** (10) **Patent No.:** **US D997,982 S**
Dye et al. (45) **Date of Patent:** **** Sep. 5, 2023**

(54) **DISPLAY SCREEN OR PORTION THEREOF WITH GRAPHICAL USER INTERFACE**

(71) Applicant: **Apple Inc.**, Cupertino, CA (US)

(72) Inventors: **Alan C. Dye**, San Francisco, CA (US); **Vincent Lane**, San Francisco, CA (US); **Alexander Charles MacLean**, San Jose, CA (US); **Wyatt R. Mitchell**, San Francisco, CA (US); **Christopher Wilson**, San Francisco, CA (US)

(73) Assignee: **Apple Inc.**, Cupertino, CA (US)

(**) Term: **15 Years**

(21) Appl. No.: **29/732,097**

(22) Filed: **Apr. 21, 2020**

Related U.S. Application Data

(63) Continuation of application No. 29/642,772, filed on Apr. 2, 2018, now Pat. No. Des. 884,720, which is a continuation of application No. 29/567,774, filed on Jun. 13, 2016, now Pat. No. Des. 816,117.

(57) **CLAIM**

The ornamental design for a display screen or portion thereof with graphical user interface, as shown and described.

DESCRIPTION

FIG. 1 shows a display screen or portion thereof with graphical user interface showing our new design; FIG. 2 shows another embodiment thereof; and, FIG. 3 shows another embodiment thereof.

The peripheral dashed broken lines illustrate a display screen or portion thereof, and form no part of the claimed design. The dashed broken lines within the peripheral dashed broken lines illustrate portions of the graphical user interface which form no part of the claimed design.

1 Claim, 3 Drawing Sheets
